UNITED STATES PATENT OFFICE

HENRY MARLES, OF DETROIT, MICHIGAN, ASSIGNOR TO GEMMER MANUFACTURING COMPANY, OF DETROIT, MICHIGAN, A CORPORATION OF MICHIGAN

BUSHING

Application filed October 18, 1926. Serial No. 142,434.

This invention relates generally to bushings and refers more particularly to an improved form of bushing of the type set forth in United States Patent No. 1,475,344.

As set forth in the patent, the outwardly bowed fingers 6 extend longitudinally of the bushing and are terminally connected to the end portions thereof, hence the fingers are not capable of flexing independently of each other or of the end portions of the bushing. Moreover spaced portions of the metal blank have to be removed and scraped during the manufacture of such bushings to form the parallel tongues 6. In the use, the end portions 7 of each bushing will be moved longitudinally when one or more of the fingers flexes. Hence should only one or two of such fingers at one side of the bushing flex at one time and thereby flatten out into substantially the longitudinal plane of the end portions 7, the bushing would be unable to provide the proper resilient or cushioning effect, hence the outer casing 2 would strike against the end portions 7 as well as the flattened fingers and would set up an objectionable noise.

In the present instance I have overcome the objectionable features of the bushing set forth in the Patent 1,475,344 by providing a more resilient bushing that it constructed in such a way that the spring fingers are capable of flexing independently of each other and independently of the end portions of the bushing. Hence the fingers of my improved construction will always provide the proper resilient or cushioning effect and objectionable noises will be obviated entirely.

In the accompanying drawing:

40 Figure 1 is a top plan view of a blank after the slotting operation.

Figure 2 is an edge view thereof.

Figure 3 is a side elevation of a bushing embodying my invention.

45 Figure 4 is an end elevation of the construction shown in Figure 3.

Figure 5 is a side elevation of the bushing applied to the steering column.

Referring now to the drawing, 1 is a 50 bushing embodying my invention for use

between telescoping members such as for instance, the normally concentric shaft 2 and casing 3 of a steering column. As shown, this bushing 1 is preferably cylindrical in form and is provided intermediate its ends 55 with a circumferential series of outwardly projecting substantially V-shaped fingers 4. To provide an efficient construction these fingers 4 are preferably curved longitudinally and are arranged in tandem about the 60 bushing with the apices of the V's arranged in a plane perpendicular to the axis of the bushing. Hence, any one of the fingers 4 may flex independently of the others and independently of the end portions of the bushing. 65

In the process of construction, a flat blank 5 is first stamped to the desired shape with the fingers cut therein as shown in Figures 1 and 2. Inasmuch as the slots 6 are substantially V-shape and are spaced apart longitudinally of the blank, the metal between the slots may be utilized for the tongues. Following the slotting operation the blank 5 is rolled into the cylindrical form so that 70 the metal between the slots will be projected laterally outwardly to form the fingers 4 as shown in Figures 3 and 4.

In the use the bushing may be sleeved 75 upon any cylindrical object for cushioning a surrounding object. In the present instance it is sleeved upon the shaft 2 so that the fingers 4 will engage and provide the proper resilient and cushioning effect for the outer tube or casing 3. Should the outer casing 3 move toward the inner shaft 2 the adjacent fingers 4 will flex independently of the other fingers and of the end portions 8 to cushion the outer casing 3. Thus the bushing will not become distorted and will 80 not permit the outer casing 3 to set up any objectionable noise by contacting with the end portions 8. Hence the bushing just described is more resilient and therefore more efficient for the purposes set forth. 85

While it is believed that from the foregoing description, the nature and advantage of my invention will be readily apparent, I desire to have it understood that I do not limit myself to what is herein shown and de- 95 100

scribed and that such changes may be resorted to when desired as fall within the scope of what is claimed.

What I claim as my invention is:

- 5 1. A bushing having a tubular body and a series of outwardly projecting substantially V-shaped fingers curved longitudinally of said bushing and arranged in tandem about the body and extending substantially tangential thereto.
- 10 2. A bushing having a tubular body and a circumferential series of substantially V-shaped fingers curved longitudinally of said bushing and projecting substantially tangential to the body and arranged in tandem with the apexes of the V's in a plane substantially perpendicular to the axis of the bushing.
- 15 3. A bushing having a cylindrical body and a series of independently movable projections extending tangentially from and curved longitudinally of the body portion.
- 20 4. A bushing having a series of independently movable substantially V-shaped projections, the apexes of the V's projecting outwardly beyond the plane of the bushing and the legs of the V's formed integral with the bushing.
- 25 5. A bushing having a body portion formed with a series of longitudinally extending slots, the portion of the bushing defining one longitudinal edge of the slots being bent outwardly forming resilient fingers.

In testimony whereof I affix my signature.
